UNITED STATES PATENT OFFICE

WILLIAM F. PUNTE, OF SYRACUSE, NEW YORK, ASSIGNOR TO CONTINENTAL CAN COMPANY, INC., OF NEW YORK, N. Y., A CORPORATION OF NEW YORK

METAL CONTAINER

Application filed April 3, 1931. Serial No. 527,583.

The invention relates to new and useful improvements in metal containers, and more particularly to a metal container of the rip strip type provided with an inserted collar 5 with which a cover makes slip engagement for re-closing.

An object of the invention is to provide a collar for a container of the above type made from a strip of metal having the ends thereof 10 locked together by the inter-engaging and folding of metal parts disposed relative to each other, so that the outer face of the collar is of uniform diameter and makes intimate contact with the inner face of the body wall 15 of the container throughout the entire circumference of the collar.

In the drawing—

Figure 1 is a sectional view through a container with the improved collar inserted 20 therein;

Fig. 2 is a sectional view on the line 2—2 of Fig. 1, and

Fig. 3 is a view showing the ends of the collar detached and with the holding lugs 25 positioned at right angles to the face of the collar, and also showing the depressions in the inner lap which are formed when the lugs are turned down and pressure applied thereto.

The invention is directed to a metal container which includes a body portion having the ends joined thereto preferably by double seaming. The body wall adjacent one of the 30 double seams is provided with score lines 25 setting off a rip strip to which a key may be attached for tearing away the metal to separate the end from the body, thus opening the container. Within the body is an inserted collar which makes tight frictional grip-

ping contact with the inner wall of the container body. This collar is in the form of a strip having the ends thereof secured together by an interlocking and folding of the metal parts at the ends of the strip. The ends 40 of the strip overlap each other. The inner

lapping end is provided with an elongated opening extending lengthwise of the strip. The other end of the strip is provided with lugs which are cut from the strip and bent so as to extend at right angles thereto. These 50 lugs are so positioned that they pass through said elongated opening, after which the lugs are folded down against the inner face of the strip. After the lugs have been folded down, pressure is applied and this will cause 55 the lugs to form depressions in the inner lapped section, forcing the depressions into the openings in the outer lapped section formed by striking up the lugs. The end of the inner lapping portion is offset from the body of the strip so that the outer face of the strip is of uniform diameter throughout, and will make intimate frictional contact with the inner face of the wall of the container 60 body.

Referring more in detail to the drawing, the metal container as shown includes a body portion 1 which is preferably cylindrical in shape. Only one of the ends is shown. This end is indicated at 2 and it is secured to the body portion 1 by a double seam 3. The wall of the container body is provided with a score line 4 and also a score line 5. These score lines 4 and 5 set off a ripping strip 6 to which a key may be applied for tearing away the 70 ripping strip and thus releasing the end or cover 2 from the container body. Inserted within the container prior to the applying of the end thereto, is a collar 7. The collar 7 has the ends thereof lapped and secured 75 together. The end 8 of the collar is the outer lapping portion. This end is provided with lugs 9 and 10 which are struck up from the metal in the collar, and are initially formed so as to extend at right angles to the face of the collar. In striking up the lug 9, an opening 11 is formed, and by the striking up of the lug 10, an opening 12 is formed.

The end 13 of the collar band is the inner 80 lapping end. This end 13 either prior to the

joining of the ends, or during the joining of the ends, is offset along the line 14 so that the end portion 13 of the collar lies in a line parallel with the longitudinal axial line of the collar and offset therefrom the thickness of the metal of the collar. This is to provide a construction so that when the two ends are joined, the outer face of the collar adjacent the line 14 on one end of the collar, will be flush with the outer face of the other end of the collar. This produces a collar, which as clearly shown in Fig. 2, is of uniform diameter throughout, and therefore, the outer face of the collar will make intimate contact with the body wall 1 of the container, as shown in this figure. The end 13 of the collar is provided with an opening 16 therethrough adapted to receive the lugs 9 and 10. After the lugs have been inserted in this opening, they are folded down on to the inner face of the end section 13, and pressure applied. The pressure will cause the metal at the ends of the opening 16 to be depressed or forced into the openings 11 and 12 as indicated at 15, 15. This not only aids in the locking of the two ends together, but it also produces a construction wherein the lugs are substantially flush with the inner face of the lapping section 13. The upper edge of the section 13 is inclined as indicated at 17, so as to avoid any sharp inner corner at the upper edge portion of the collar.

From the above it will be apparent that I have provided a collar for insertion in a container body which is formed from a strip of metal having the ends thereof firmly locked together by an interlocking and folding of the metal parts of the collar. These parts are so disposed that the outer face of the collar is substantially of uniform diameter throughout so that when it is placed within the container body, it will make intimate contact with the inner wall of the container body substantially throughout the entire circumference of the collar. After the container is opened, the material in the container is passed through the collar in the dispersing of the contents of the container. If the content is of a liquid type, then it is quite essential that the collar shall make a liquid-tight joint or connection with the body wall throughout the entire circumference of the collar. Otherwise, the liquid will pass under the collar and will run down the outer wall of the container instead of through the collar and discharge from the outer lip edge of the collar. No matter whether the liquid content is poured from the container over the connection between the ends of the collar or at any other place, there is no chance for escape of the liquid beneath the collar, for the reason that the collar, when the ends are joined, as described above, makes an intimate liquid-tight contact with the container wall throughout the entire region where the ends are joined.

Furthermore, when the ends of the collar are joined by an interengaging and folding of the parts of the collar, there is no slippage of one end on the other when force is applied thereto, which tends to contract the collar or which tends to expand the collar. Therefore, the collar may be made so that it will have a tight frictional grip with the body wall when inserted therein, and can, at the same time, be rounded into form and forced into this tight gripping contact with the wall of the container.

The score lines 4 and 5 are so disposed in the present embodiment of the invention, that when the rip strip is removed, there will be a portion 18 of the body wall left attached to the end 2 which projects downwardly so as to make an outside slip engagement with the collar 7 for re-closure purposes. While I have shown the collar as used in connection with a container having an outside slip portion formed from the body wall, it will be understood that this depending portion remaining attached to the end and forming therewith a cover, may be otherwise formed. Likewise, the collar instead of being substantially of uniform diameter throughout and without any rolled edge, may be otherwise shaped. The essential features of the invention reside in the joining of the ends of the collar so that the outer surface of the collar is of substantially uniform diameter throughout.

Having thus described the invention, what I claim as new and desire to secure by Letters Patent, is—

1. A metal container comprising a body portion, an end secured thereto, said body portion having spaced score lines forming a rip strip whereby the end may be released from the body of the container, and a collar inserted within said body and positioned so as to overlie the rip strip, one end of said collar having an offset portion overlying the other end of the collar, one end of said collar having an opening therethrough and the other end of said collar having a lug struck up from the metal forming an opening adjacent the lug, said lug extending through the opening in the other end of the collar and folded down against the face of the end of the collar and depressing a portion of said end into the opening formed by striking up the lug.

2. A metal container comprising a body portion, an end secured thereto, said body portion having spaced score lines forming a rip strip whereby the end may be released from the body of the container, a collar inserted within said body and positioned so as to overlie the rip strip, one side of said collar having an offset portion overlapping the other end of the collar on the inner face thereof, said outer overlapping end of the collar having lugs struck up from the metal form-

ing openings adjacent the lugs, the inner overlapping end of the collar having an opening therethrough adapted to receive said lugs, and depressed portions at the ends of 5 the opening formed by the lugs when folded down and pressure is applied thereto, which depressions extend into the openings formed in the outerlapping section by the striking up of the lugs.

10 In testimony whereof, I affix my signature.

WILLIAM F. PUNTE.
